HOWARD R. HUGHES, Inventor

UNITED STATES PATENT OFFICE.

HOWARD R. HUGHES, OF HOUSTON, TEXAS.

ROTARY BORING-DRILL.

1,200,170.

Specification of Letters Patent. Patented Dec. 31, 1918.

Application filed July 30, 1918. Serial No. 247,367.

To all whom it may concern:

Be it known that I, HOWARD R. HUGHES, a citizen of the United States, residing at Houston, Harris county, Texas, have invented a certain new and useful Improvement 5 in Rotary Boring-Drills, of which the following is a full, clear, and exact description, such as will enable others skilled in the art to which it appertains to make and use 10 the same.

My invention relates to rotary boring drills, and has particular reference to drills of the roller type for use in digging wells or mines in earth, rock or other similar material.

It has for its object the provision of a means for housing the cutters of a drill of the character described, said housing being removable.

Another object is to provide a detachable housing for the cutters which may be easily and quickly removed and which may be firmly secured against accidental removal during the operation of the device.

Other objects and advantages of my invention will more clearly appear in the description which follows, and will be pointed out with more particularity in the claims.

Referring to the drawing forming a part 30 of this specification, and wherein like numerals of reference are applied to like parts throughout the several views, Figure 1 is a side elevation showing my invention in use on a cone bit. Fig. 2 is a bottom plan view 35 of the same. Fig. 3 is a top plan view of the housing removed from the bit. Fig. 4 is a side view of the housing disclosed in Fig. 3, the right hand side of the same being shown in section on the line 4-4 of Fig. 3; and Fig. 5 is a projection taken from Fig. 4 showing the flat side of the housing.

I have shown my invention in use upon a rock bit of the cone type, this bit being substantially the same as that disclosed in my 45 Patent No. 930,759, patented August 10, 1909. This drill is made up of a longitudinal, approximately cylindrical-shaped head, 5, having a reduced upper shank, 6, threaded for attachment to the drill stem, not shown. 50 The lower end of this head is provided with inclined flat inner faces upon which are mounted two opposite cone-shaped cutters, 7, these cutters being closely housed within a socket, 8, in the base of the head. Two 55 opposite sides of the head are flattened, as shown at 12, to allow a free upward passage

of the flushing water which is used in rotary drilling for the purpose of carrying upwardly the disintegrated matter. Reaming rollers, 9, are mounted on the two flattened sides of 60 the head in sockets, 10, these rollers being adapted to roll upon the side of the hole and to assist in maintaining the gage of the hole in order to prevent any wedging or sticking of the bit in the hole. The head of 65 the bit is divided longitudinally on a line, 11, in a plane at right angles to the flattened sides, 12.

The manner in which the cutters are shrouded or inclosed for purposes of protection and for maintaining the flushing water directly upon the cones is one of the principal features of my invention. The cutters are shrouded by means of a web, 13, fitting between the two sides of the head and 70 having a flat portion extending from the cutters upward approximately half the length of the head. This web has the said flattened upper portion, 14, for purposes of 75 attachment in the head, and a lower shrouding portion, 15, so formed as to fit closely about the cutters. Each side of the web is formed with a side wall, 16, projecting inwardly between the cutters and adapted to conform to the shape of the cones. From the 80 central indentation, 16, in the shroud the walls of the same are extended outwardly around the cutters so as to shroud approximately one half of the same. This outward extension is indicated at 17, and is curved 85 to conform to the cylindrical shape of the head. On the inner side of the inclosing wall the socket formed by the shroud is extended upwardly and conforms to the curved 90 upper portion of the two cutters, as shown 95 at 18 in Fig. 4.

The flushing water is introduced through longitudinal channels, 19, in the head. The water passes downwardly through the head and through registering channels, 20, in the 100 housing, 13, and is introduced into the socket in which the cutters are inclosed. One channel is provided on each side of the bit for conveying water to the cutting cones. In this manner the flushing water, which is 105 projected downwardly through the channels, 19, in the head and through the registering passages, 20, in the shroud, issues into the socket in such manner as to be forced outwardly through the socket and around the 110 cutters with some force. The cutters are so closely inclosed by the shroud that only a

small passage is provided on all sides of the cutters and the water is projected outwardly from the shroud through the constricted opening around the cutters, with somewhat 5 the effect of a hose nozzle, thus serving to wash away any disintegrated matter which may adhere to the cutters, and to keep them clean at all times.

In order to prevent any lateral or longitudinal 10 movement of the shroud during the cutting operation, and thus to prevent any interference of the shroud with the cutters, I have provided a pin, 21, shown at dotted lines in Fig. 1, this pin passing diametrically 15 through the head at right angles to the plane of the upper web, 14, of the shroud. A hole, 22, is provided in the web to receive the said pin.

By the use of this inclosing shroud in relation 20 to the cone bit the cutters may be adapted for operation in the softer formations. The cone bit is especially adapted, under ordinary circumstances, for use in drilling rock, and without some means of 25 preventing the lodging of softer material, such as gumbo or clay, about the cutters, the teeth thereof will become so clogged that no cutting action will be possible. But by the use of the shroud herein shown, the 30 water is so constricted in its passage outwardly as to be forced with considerable pressure from the sides of the housing, and thus maintain the cutters free of the disintegrated material.

In assembling the structure, the pin, 21, is removed and the two parts of the head separated in such manner that the upper part of the web, 13, may be mounted between the two sides of the head and the lower part thereof 40 to fit closely about the cutters. The two parts of the head are then moved into contact with each other in such manner that the cutters will fit closely into the socket in the lower part of the shroud and so that the 45 holes in the two parts of the head will register with the hole, 22, in the upper part of the web. The pin, 21, is then inserted and secured in position. The pin, 21, will thus not only serve to secure the shroud in proper 50 position but will serve to hold the two parts of the divided head together. This service is also assisted by means of the drill collar, which may then be secured about the upper threaded shank, 6, of the head, and thus prevent 55 any lateral movement at the upper end of the bit.

Having thus described my invention, the objects and advantages of which will be clear without further description, what I 60 claim as new, and desire to protect by Letters Patent, is:

1. In a rotary boring drill, a head, cutters rotatably mounted in the base thereof, a

shroud for said cutters comprising a removable section fitting within a slot in said head, 65 the said shroud being recessed to house said cutters on all but the active cutting portion, and a pin adapted to pass through said head and slot to engage said shroud and secure the said shroud in position. 70

2. In a rotary boring drill, a head, cutters rotatably mounted thereon, and a single removable shroud for said cutters adapted to fit between said cutters and to be secured within a slot in the base of said head, the said shroud having two inwardly bent side walls 75 completely closing the space between said cutters and closely housing the same.

3. In a rotary boring drill, a head, cutters rotatably mounted thereon, a shroud for said cutters comprising a flat removable section adapted to fit within a slot in the lower part 80 of said head, the lower end of said section being so recessed and shaped as to closely surround said cutters, and means to retain 85 said section in adjusted position.

4. In a rotary boring drill, a head, cutters rotatably mounted in the lower end thereof, a housing for said cutters comprising a single removable section fitting slidably 90 within a central slot in said head, the lower end of said housing having two lateral inwardly projecting walls shaped to closely house said cutters, and means to secure said housing against accidental removal. 95

5. In a rotary boring drill, a head divided longitudinally in two parts, recesses in the inner face of said parts toward the lower end thereof, cutters mounted in the base of said head, and a web fitting within said recesses, the upper end thereof being flat and 100 slideable therein, the lower end of said web shaped to conform to the curvature of the cutters and to closely house said cutters on the upper side thereof. 105

6. In a rotary boring drill, a head, cutters rotatably mounted in the base, a shroud for said cutters, said shroud having a flat upper shank fitting removably within a slot in the head and the lower end portion shaped to 110 conform to the contour of the cutters, and a single transverse locking pin adapted to secure the shroud within the head.

7. In a rotary boring drill, a head, cone shaped cutters rotatably mounted in the 115 base thereof, and a shroud for said cutters comprising a single web fitting within a central slot in the base of said head, the lower part of said web shaped to fit closely around said cutters on all sides, except the outer cutting portion.

In testimony whereof, I hereunto affix my signature this the 26th day of July, A. D. 1918.

HOWARD R. HUGHES.
